United States Patent Office

Des. 208,866
Patented Oct. 10, 1967

208,866

FIGURINE

Sam Bernardi, 5252 Corteen Place,
North Hollywood, Calif. 90028

Filed May 27, 1966, Ser. No. 2,446

Term of patent 3½ years

(Cl. D29—23)

FIG. 1

FIG. 2

FIG. 3

FIG. 4

FIG. 1 is a front view of a figurine showing my new design;

FIG. 2 is a top view thereof;

FIG. 3 is a side view looking from the right of FIG. 1; and

FIG. 4 is a side view looking from the left of FIG. 1. I claim:

The ornamental design for a figurine, substantially as shown.
